VAT DYE COMPOSITIONS CONTAINING
MIXED DIAMIDES OF DIBASIC ACIDSRoy Herman Kienle and Chester Albert Amick,
Bound Brook, N. J., assignors to American Cy-
anamid Company, New York, N. Y., a corpora-
tion of MaineNo Drawing. Application July 1, 1943,
Serial No. 493,135

11 Claims. (Cl. 8—70)

This invention relates to a new type of dyeing and printing assistant, dye compositions containing these assistants and products printed therefrom.

Use of printing-color pastes containing dyes, particularly in printing operations using vat dyes, is sufficiently well-known so that the procedure has become almost standardized. The actual color source may be either a dye paste or a dye powder. In addition to the real color, a dye paste usually contains agents to prevent drying-out, settling and/or freezing. Dye powders, not being subject to these difficulties, do not require these agents but they usually contain agents or are so processed as to promote dispersibility.

In either case, the dye paste or dye powder must be admixed with suitable thickener, usually a gum dispersion, to form a printing-color paste which is suitable for application. In the case of vat dyes, it is also necessary to add a reducing agent and usually an alkali. Because the color yield from printing-color pastes often decreases rapidly as the paste ages after being made up, these printing color pastes are usually prepared by the fabric finishers just before they are to be used.

The printing-color pastes, however compounded, are then applied to textile, paper or other fabric materials for decorative or protective purposes. The printed pieces are dried, aged in a steam ager, treated with an oxidizing agent, rinsed and finally dried. Usually in processing textiles, the printed fabric also is soaped at or near the boil with about a 0.1% soap solution and again rinsed before the final drying operation.

In making up and applying printing-color pastes it has been found that a material suitable for use as a printing assistant is of advantage in obtaining maximum color yield. The exact way in which these materials act to produce an improved color yield in printing is not entirely understood. It is with these printing aids or assistants that the present invention is particularly concerned.

Although printing aids are desirable in the printing-color pastes, the exact point at which they are added may vary. Dye pastes may contain printing aids as one of their components and printing-color pastes made therefrom will obviously contain the printing assistant. Where a printing assistant is not present in the dye paste, it may be added at the time of making up the printing-color paste.

It is preferable, however, that the printing assistant be incorporated in the actual dye paste.

Their addition at the proper point in the manufacture of the paste is not only easier, but in addition they are thus generally more uniformly dispersed throughout a printing-color paste made therefrom. As a result, the printing assistants usually operate more effectively when the printing-color paste is finally applied to the fabric.

It is only relatively recently that dye powders suitable for use in making up printing-color pastes have been available. Most of the printing aids previously used in dye pastes, being either liquid in form or extremely hydroscopic, can not be used with dye powders, the latter being necessarily limited to the use of dry solids. Nevertheless, it is desirable that printing assistants be incorporated in the powders at the time of manufacture for the same reasons which apply in the case of dye pastes.

Dye pastes containing various liquid printing assistants have been made. Among the liquid materials used are the alkylol amines, for example, triethanol amine; and/or polyhydric alcohols such as glycerine, glycol, diethylene glycol and the like. Various derivatives therefrom also have been tried. If a printing aid is to be incorporated in a dye powder, a solid printing aid is necessary. Examples of such solids which have been used in the past include the hydrochlorides of alkylol amines; silver salt (sodium anthraquinone beta-sulfonate); anthraquinone and certain metal salts such as those of cobalt and iron.

Unfortunately, most of these printing aids previously used are not as satisfactory as may be desired. Many of them will not in all cases produce the intensification of color for which they were intended. Others, such as the polyhydric alcohols, cause deterioration of the printing-color pastes so that marked variations in the strength of prints therefrom are observable even after the printing-color paste has been allowed to stand for only a relatively short time. Many of them are satisfactory with some colors but have an adverse effect on others, even to the extent of visibly altering the shade. None of them are suitable without modification for use both in paste and powder compositions.

There remains, therefore, a demand for suitable printing assistants which will produce a satisfactory color intensification and will not cause deterioration of the dyeing or printing composition on standing. Preferably also, the assistants should be useful both with dye pastes and dye powders and in addition should be readily available or cheaply and easily prepared. It is, therefore, the object of the present invention to pro-

vide a new type of printing assistant which possesses these desirable properties.

In general the object of the present invention is accomplished by using as a printing assistant one or more of the mixed diamides of dicarboxylic acids represented by this type formula

in which Ac represents the residue of a cyclic or aliphatic dibasic acid, Q represents a quinonyl group and R represents the residue of an alkyl, aryl or alkaryl group. Typical of the mixed amides suitable for use according to the present invention is the N(alpha anthraquinonyl) N' (ethanol) diamide of fumaric acid which has the probable formula

so far as the present invention is concerned the assistants may be added to the printing-color pastes at any point. They may be incorporated into the thickener; into the dye pastes or powders or may be blended directly into the printing-color paste. However, as pointed out above, it is preferable that they be incorporated in the dye paste or powder during manufacture.

The use of this new class of printing assistants possesses a number of important advantages. These compounds are dry solids, which may be readily powdered and blended in dye powders but are also soluble or dispersible in dye paste suspensions. They have, therefore, a general application in both dye pastes and dye powders. They do not cause deterioration of printing-color pastes on standing. They encourage the production of excellent color yields even under hot ageing conditions. Their use is simple since they may be employed as powders, as suspensions in water or alcohol, producing excellent color yields whatever the mode of admixture.

In preparing the compounds to be used as the printing assistants of the present invention the dicarboxylic acid may be quite widely varied. The compounds may be derived from either cyclic or aliphatic dicarboxylic acids. Of the cyclic carboxylic acids, phthalic acid is perhaps the most common and its derivatives have been found to give good results when used according to the present invention. The invention however is not meant to be so limited but includes derivatives of such acids as isophthalic, terephthalic, polyhydrophthalic, endoalkylene polypolyhydrophthalic acids such as endomethylene tetrahydrophthalic, endoethylene hexahydrophthalic and the like, and the naphthalic acids as well as substituted acids derived therefrom.

Where derivatives of aliphatic dicarboxylic acids are used, the original acid or anhydride may be varied over a considerable range. If the original aliphatic acid is considered to have the generic formula

or anhydride

in the case of the anhydride, y may have substantially any value from zero as in the case of oxalic acid to about eight without departing from the scope of the present invention. However, where y is greater than about six, trouble is encountered in preparing the derivatives. Above about y=8, there is a tendency for the compounds to be too insoluble for satisfactory use. The acids may be either saturated acids such as malonic, succinic, glutaric, adipic, azelic, sebacic, and the like or unsaturated such as maleic, fumaric, and the like.

As pointed out in connection with the generic formula, Q represents a quinonyl group such as those of the naphthoquinones and anthraquinones. Paraquinonyl derivatives such as those from alpha-naphthoquinone and p-anthraquinone were found to give particularly good results according to the present invention. The invention however is not necessarily so limited. Similarly good results were obtained, for example, from the derivatives of beta-naphthoquinone and beta-anthraquinone.

In preparing the printing assistants of the present invention R also may be quite widely varied without departing from the intended scope. In general, the group

may represent the residue after amidation of a wide range of alkyl, aryl or alkaryl amines. Of the aliphatic amines which were found to give excellent results according to the present invention, good examples are the primary and secondary alkyl amines and hydroxy amines such as primary ethyl amine, ethanol amine, ethylene diamine, propylene diamine, butyl amine and the like. Where the aliphatic group contains more than about five or six carbon atoms trouble is encountered in that the diamides tend to be too insoluble. There is also some tendency toward polymerization.

As pointed out, however, the invention is not limited to the use of aliphatic amines. Aryl amines such as aniline, diphenylamine, the alpha- and beta-naphthylamines and the like produce excellent printing assistants. Similar results are also obtained using mixed diamides of a dicarboxylic acid, a quinonyl amine and such alkaryl amines as the toluidines, xylidines and the like.

Theoretically, R and Q may both be the same or different quinonyl radicals or the same or different residues of other amines. However, the present case is not intended to extend to such a scope. The specific case where both $(-\text{NH}-\text{R})$ and Q are similar quinonyl groups is set forth in our copending application for U. S. Letters Patent, Serial No. 493,134, filed of even date, and the case where $(-\text{NH}-\text{R})$ and Q are the residues of the same or different amines, neither being a quinonyl group, is covered in our copending application for U. S. Letters Patent, Serial No. 493,136, filed of even date.

In preparing the compounds to be used in the present invention one feature should be noted. The diamides may be prepared from a mono-quinonyl amide by reaction of the latter with another amine, forming the diamide by the elimination of a second molecule of water. Heat is

required to carry out this reaction to form a true diamide. However, a compound which may be designated as a salt ordinarily forms on treating a monoquinonyl amide of a dicarboxylic acid with a second amine at a low temperature. These salts are also useful in carrying out the teachings of the present invention but are not intended to be within the scope of the present application, being set forth specifically in our pending application for U. S. Letters Patent, Serial No. 493,130 filed of even date.

While the dye and printing paste compositions of the present invention are not limited to the use of any particular dyes or dye forms, they are especially suitable for use with vat-dyes in either paste or powder form. Particularly good results may be obtained using the vat-dye powders of high autodispersibility set forth in Crossley et al., United States Reissue Patent No. 21,402, reissued March 19, 1940. By combining the color materials of that patent into printing-paste compositions containing the printing assistants of the present invention, the full advantages of both may be gained with a resultant simplicity in use and excellence of shade and sharpness of color.

Printing pastes made in this way have the particular advantage that the dyes remain in a highly dispersed state as individual particles rather than as dispersions of particle aggregates. In the present specification and claims, where highly-dispersed dyes are referred to, reference to pastes in which the dye particles are so dispersed is intended.

The invention will be more fully set forth in connection with the following examples which are intended to be illustrative and not by way of limitation. All parts are by weight unless otherwise noted.

In the succeeding examples, test prints were made on two different fabrics. Where rayon is referred to, a titanium-dioxide-pigmented, all-viscose-rayon-flat-crepe was used. The cotton fabric referred to is an 80 x 80 bleached, unmercerized, cotton print-cloth. Ageing of the prints was carried out in a steam ager which was constructed in such a manner that controlled temperatures could be used. The temperature range normally used was 100°-105° C. Those ageing referred to as plant or hot ageing were carried out in the temperature range of about 106°-110° C. In the case of the cotton prints ageing periods of 3 minutes, 5 minutes or both were used. On rayon, ageing periods of 5 and 10 minutes or both were used. The shortest period which gives a satisfactory ageing is preferable.

Example 1

2,100 parts of B-2 British gum, 200 parts of tapioca flour and 500 parts of cornstarch were added to 2,500 parts of water and heated over a steam bath for approximately 1½ hours after the temperature reached about 185° F. The source of heat was then removed but stirring was continued until the temperature decreased to 130° F. at which time 2,100 parts of potassium carbonate which had been previously dissolved in hot water was added to the cooked gum. 1,100 parts of sodium sulfoxylate formaldehyde were added to the common mixture at a temperature of about 150° F. Subsequently, 1,400 parts of glycerine were added and after thorough stirring the whole was bulked to about 10,000 parts. The mixture was cooled and stirred continuously until the mass reached room temperature. In the suc-

ceeding examples this mixture is referred to as thickener A.

Example 2

5 720 parts of B-2 British gum and 720 parts of KAC-4 gum (Stein Hall) were added to 5,600 parts of water and heated over a steam bath for approximately 1½ hours after the temperature reached 185°-190° F. The source of heat was then removed but stirring was continued until 10 the temperature decreased to 120° F. at which time 1,200 parts of potassium carbonate which had been previously dissolved in 1,000 parts of water was added to the cooked gum. 1,560 parts of sodium sulfoxylate formaldehyde were dissolved in 1,500 parts of water at a temperature of about 140° F. and added to the common mixture with stirring until the whole was thoroughly mixed. Finally, 360 parts of glycerine were added and after thorough stirring the whole was 15 bulked to 12,000 parts. In the succeeding examples this mixture is referred to as thickener B.

Example 3

10 parts of Dark Blue BO dispersed powder 25 (C. I.—1099), prepared according to U. S. Reissue Patent 21,402 and containing about 3.7 parts of real dye were mixed with 90 parts of thickener B. This was the control sample. A second 10 parts of the Dark Blue BO dispersed powder was 30 blended with 0.3 part of N ethanol, N' (beta-anthraquinonyl) maleic acid diamide. To this mixture 90 parts of thickener B was added and thoroughly mixed. Each of these pastes were printed on rayon and cotton. The printed pieces 35 were then dried in a hot-air dryer at a low temperature and aged in a steam ager. After ageing, the pieces were oxidized, soaped at the boil for 5 minutes in a 0.1% soap solution, again rinsed and finally ironed dry. Prints obtained 40 from the paste containing the mixed amide gave stronger color yields than those prints made from the control sample. This was particularly noticeable with the cotton print cloth when aged under plant ageing conditions.

Example 4

The procedure of Example 3 was duplicated except that 10 parts of Golden Orange G powder 50 (C. I.—1096), containing about 1.9 parts of real dye was used. The prints obtained from the paste containing the mixed amide were appreciably stronger than those obtained from the paste containing water only.

Example 5

6 parts of a dispersible Orange R powder 55 (C. I.—1217), prepared according to U. S. Reissue Patent 21,402 and containing about 2.4 parts of real dye, were blended with 0.6 part of the mixed diamide of Example 3 and 13.4 parts of water. To this mixture was added 80 parts of thickener A. A second 6 parts of the Orange R powder was pasted with 14 parts of water and blended with 80 parts of thickener A. Each of these 60 pastes were printed on rayon in the usual manner. The prints made from the paste containing the mixed diamide of maleic acid were definitely superior to those made from the printing paste containing no assistant.

Example 6

The procedure of Example 5 was repeated except that N ethanol, N' (beta-anthraquinonyl) fumaric acid diamide was used as the printing assistant. The prints obtained from the paste con-

taining the mixed amide gave very definitely stronger and brighter color values than those obtained from the paste containing water only.

Example 7

A sample of Vat Orange R wet presscake (C. I.—1217) was dispersed with the sodium salt of disulfodinaphthyl methane and adjusted with water to contain about 12% real dye. 10 parts of this slurry were mixed with 0.3 part of N ethanol-N' (beta-naphthoquinonyl) maleic acid diamide after which 90 parts of thickener B were added and the whole intimately mixed. A second 10 parts of the orange color was used likewise and mixed with 90 parts of thickener B, but the printing assistant was omitted. Prints made from the paste containing the printing assistant were stronger on both cotton and rayon than those obtained from the paste containing water only.

Example 8

The procedure of Example 7 was duplicated except that N (beta-anthraquinonyl) N' (alpha-naphthyl) maleic acid diamide was used in place of the beta-naphthyl product of the preceding example. The prints obtained from the paste containing the printing assistant were definitely stronger and brighter than those obtained from the pastes containing water only.

Example 9

The procedure of Example 7 was followed exactly except that maleic acid diamide was replaced by the N (beta-anthraquinonyl) N' ethanol succinic acid diamide. The color values obtained from this assistant were also definitely superior to those obtained from the printing pastes in which it was omitted.

Example 10

Another set of comparative pastes were prepared according to Example 7 except that N (beta-anthraquinonyl) N' ethanol phthalic acid diamide was used as a printing assistant. Again the color values obtained from the paste containing the printing assistant were much stronger and brighter.

Example 11

The procedure of Example 7 was repeated using N (alpha-anthraquinonyl) N' ethanol maleic acid diamide instead of N (beta-naphthoquinonyl) N' ethanol diamide as the printing assistant. Both pastes were printed on cotton and rayon. The prints obtained from the paste containing the diamide of maleic acid were much stronger than those obtained from the paste containing water only.

Example 12

N (alpha-anthraquinonyl) N' ethanol fumaric acid diamide was used as the printing assistant in the procedure of Example 7. Prints obtained from the paste containing the diamide again were stronger and brighter than those produced from the control paste.

Example 13

The procedure of Example 7 was repeated except that the N (alpha-anthraquinonyl) N' (beta-aminoethyl) diamide of succinic acid was used as the printing assistant. Prints on both cotton and rayon obtained from the paste containing the printing assistant were stronger and brighter than those obtained from the paste in which the diamide was omitted.

5 Pastes were prepared according to the procedure of Example 7 using no assistant in the control paste and N (alpha-anthraquinonyl) N' (gamma-aminopropyl) succinic acid diamide as an assistant in the other. Prints from the sample containing the assistant were stronger on both cotton and rayon than those obtained from the control paste.

Example 14

10 15 15 The procedure of Example 7 was followed except that the mixed fumaric acid diamide was replaced by the N (alpha-anthraquinonyl) N' ethanol diamide of succinic acid. It was noted there also that the pastes containing the printing assistants gave very much stronger and brighter color yields than those obtained from the control paste.

Example 15

15 20 25 The procedure of Example 7 was followed except that the mixed fumaric acid diamide was replaced by the N (alpha-anthraquinonyl) N' phenyl succinic acid diamide was used. Again, prints obtained on both cotton and rayon from the paste containing the printing assistant were definitely stronger and brighter than those obtained from the paste containing water only.

Example 16

20 25 30 The procedure of Example 7 was followed except that N (alpha-anthraquinonyl) N' phenyl succinic acid diamide was used. Again, prints obtained on both cotton and rayon from the paste containing the printing assistant were definitely stronger and brighter than those obtained from the paste containing water only.

Example 17

30 35 35 Another set of comparative pastes were prepared according to Examples 7 and 16 using N (alpha-anthraquinonyl) N' (p-tolyl) succinic acid diamide as the printing assistant. Similar printings on cotton and rayon had better color from the paste containing the printing assistant.

Example 18

35 40 40 The procedure of Example 17 was followed except that N (beta-anthraquinonyl) N' (meta-xylyl) succinic acid diamide was used as the printing assistant. The color values obtained from this product were also definitely superior to those obtained when the printing pastes containing water only were used.

45 We claim:

1. A color composition comprising a vat dye and a dicarboxylic acid diamide represented by the formula

50 in which Ac represents the residue of a dicarboxylic acid selected from the group consisting of the phthalic acids, the naphthalic acids and the saturated and unsaturated aliphatic dicarboxylic acids of from 2 to 10 carbon atoms, Q represents a quinonyl radical selected from the group consisting of the naphthoquinonyl and anthraquinonyl radicals, and R represents the residue of an amine selected from the group consisting of the monoalkylamines and monoalkanolamines of from 1 to 8 carbon atoms, aniline, diphenyl amine, the mono-naphthylamines and their alkyl-substituted derivatives.

55 60 65 2. A composition according to claim 1 in which the dye is a thio-indigo vat dye.

3. A vat dye powder composition comprising a powdered dye and a powdered dicarboxylic acid diamide represented by the formula

70 75 in which Ac represents the residue of a dicarboxylic acid selected from the group consisting of the phthalic acids, the naphthalic acids and the saturated and unsaturated aliphatic dicarboxylic acids of from 2 to 10 carbon atoms, Q represents

a quinonyl radical selected from the group consisting of the naphthoquinonyl and anthraquinonyl radicals, and R represents the residue of an amine selected from the group consisting of the monoalkylamines and monoalkanolamines of from 1 to 8 carbon atoms, aniline, diphenyl amine, the mononaphthylamines and their alkyl-substituted derivatives.

4. A dye composition comprising a vat dye powder of high autodispersibility and a powdered dicarboxylic acid diamide represented by the general formula

in which Ac represents the residue of a dicarboxylic acid selected from the group consisting of the phthalic acids, the naphthalic acids and the saturated and unsaturated aliphatic dicarboxylic acids of from 2 to 10 carbon atoms, Q represents a quinonyl radical selected from the group consisting of the naphthoquinonyl and anthraquinonyl radicals, and R represents the residue of an amine selected from the group consisting of the monoalkylamines and monoalkanolamines of from 1 to 8 carbon atoms, aniline, diphenyl amine, the mono-naphthylamines and their alkyl-substituted derivatives.

5. A color composition according to claim 1 in which Q represents a naphthoquinonyl group.

6. A color composition according to claim 1 in which Q represents an anthraquinonyl group.

7. A printing paste composition comprising a vat dye, a thickener and a dicarboxylic acid diamide represented by the general formula

in which Ac represents the residue of a dicarboxylic acid selected from the group consisting of the phthalic acids, the naphthalic acids and the saturated and unsaturated aliphatic dicarboxylic acids of from 2 to 10 carbon atoms, Q represents a quinonyl radical selected from the group consisting of the naphthoquinonyl and anthraquinonyl radicals, and R represents the residue of an amine selected from the group consisting of the monoalkylamines and monoalkanolamines of from 1 to 8 carbon atoms, aniline, diphenyl amine, the mononaphthylamines and their alkyl-substituted derivatives.

8. A vat dye composition comprising a vat dye, a thickener and a dicarboxylic acid diamide represented by the general formula

in which Ac represents the residue of a dicarboxylic acid selected from the group consisting of the phthalic acids, the naphthalic acids and the saturated and unsaturated aliphatic dicarboxylic acids of from 2 to 10 carbon atoms, Q represents a quinonyl radical selected from the group consisting of the naphthoquinonyl and anthraquinonyl radicals, and R represents the residue of an amine selected from the group consisting of the monoalkylamine and monoalkanolamines of from 1 to 8 carbon atoms, aniline, diphenyl amine, the

mononaphthylamines and their alkyl-substituted derivatives.

9. A printing paste composition comprising a highly-dispersed vat dye, a thickener and a dicarboxylic acid diamide represented by the general formula

in which Ac represents the residue of a dicarboxylic acid selected from the group consisting of the phthalic acids, the naphthalic acids and the saturated and unsaturated aliphatic dicarboxylic acids of from 2 to 10 carbon atoms, Q represents a quinonyl radical selected from the group consisting of the naphthoquinonyl and anthraquinonyl radicals, and R represents the residue of an amine selected from the group consisting of the monoalkylamines and monoalkanolamines of from 1 to 8 carbon atoms, aniline, diphenyl amine, the mononaphthylamines and their alkyl-substituted derivatives obtainable by compounding a colloidized vat dye powder of high autodispersibility and the carboxylic acid diamide with the thickener.

10. A method of printing with vat color which comprises printing a fabric with a printing paste composition comprising a vat dye, a thickener and a dicarboxylic acid diamide represented by the general formula

in which Ac represents the residue of a dicarboxylic acid selected from the group consisting of the phthalic acids, the naphthalic acids and the saturated and unsaturated aliphatic dicarboxylic acids of from 2 to 10 carbon atoms, Q represents a quinonyl radical selected from the group consisting of the naphthoquinonyl and anthraquinonyl radicals, and R represents the residue of an amine selected from the group consisting of the monoalkylamines and monoalkanolamines of from 1 to 8 carbon atoms, aniline, diphenyl amine, the mononaphthylamines and their alkyl-substituted derivatives.

11. An article of manufacture comprising a fabric printed with a composition comprising a vat dye and a dicarboxylic acid diamide represented by the general formula

in which Ac represents the residue of a dicarboxylic acid selected from the group consisting of the phthalic acids, the naphthalic acids and the saturated and unsaturated aliphatic dicarboxylic acids of from 2 to 10 carbon atoms, Q represents a quinonyl radical selected from the group consisting of the naphthoquinonyl and anthraquinonyl radicals, and R represents the residue of an amine selected from the group consisting of the monoalkylamines and monoalkanolamines of from 1 to 8 carbon atoms, aniline, diphenyl amine, the mononaphthylamines and their alkyl-substituted derivatives.
